UNITED STATES PATENT OFFICE.

SAMUEL H. RANSOM, OF ALBANY, NEW YORK.

DESIGN FOR THE PLATES OF A COOKING-STOVE.

Specification forming part of Design No. 6,731, dated June 24, 1873; application filed April 18, 1873.

To all whom it may concern:

Be it known that I, SAMUEL H. RANSOM, of the city and county of Albany and State of New York, have invented a Design for the Plates of a Cook-Stove, of which the following is a specification:

The nature of my design is fully represented in the accompanying engraving, to which reference is made.

A represents the larger oven-door, having in its center an ornament composed mainly of a fancy cross, with bulb-like oval center at the intersection of the arms, all surrounded by scroll-work and filled in with stipple-work—the outer edge of door being a raised molding with flat surface, ornamented with space of

imitation of fret-work alternate with half-spherical raised dots. B B represent the smaller doors, with ornaments similar to A, but smaller in size, and without the stippling. C represents another door, the center ornament of which is a simple fancy cross, without the outer scroll-work, as in A.

I do not claim the outer bevel of the doors, or any of the moldings.

What I claim as my invention is—

A design for the plates of a cook-stove, substantially in the manner above-mentioned.

S. H. RANSOM.
